UNITED STATES PATENT OFFICE.

JACOB SCHOENHOF, OF NEW YORK, N. Y.

DESIGN FOR A SKIRT.

SPECIFICATION forming part of Design No. 12,045, dated November 30, 1880.

Application filed September 27, 1880. Term of patent 3½ years.

To all whom it may concern:

Be it known that I, JACOB SCHOENHOF, a citizen of the United States, residing in the city, county, and State of New York, have invented or produced a new Design for Skirts, of which the following specification is a full, clear, and exact description.

The view in the accompanying drawing represents a portion cut out from the lower part of the skirt, showing a section of the trimming, to which alone my design relates.

A is the body of the skirt, usually of black farner's satin, and B is the trimming as a whole. The trimming B consists of an embroidered band, C, extending parallel to the bottom edge of the skirt, and a knife-plaiting, D, filling the space between said band and the bottom of the skirt. The embroidery on the band C consists of a design of leaves and berries, as shown, preferably worked in colored silk, and extending centrally through the band. The edges of the band are decorated with colored lines *a a*, formed by sewing on a strip of edging. The plaiting D has vertical, or nearly vertical, plaits, and is provided with a colored

line, *b*, at or near to and parallel with its bottom edge, this line corresponding to the lines *a a*.

The band C and plaiting D are preferably of the same material and color as the skirt, though they may be of different color therefrom, if desired.

I claim—

The improved design for skirt-trimmings, consisting of the band C, extending parallel with the bottom of the skirt, embroidered with a design of leaves and fruit, and flanked by colored lines *a a*, in combination with the plaiting D, arranged in the space between said band and the bottom edge of the skirt, and provided with the colored line *b*, substantially as shown and described.

In witness whereof I have hereunto signed my name in the presence of two subscribing witnesses.

JACOB SCHOENHOF.
